UNITED STATES PATENT OFFICE

95,718

DESIGN FOR AN AUTOMOBILE BODY

Alexander E. Voigt, Philadelphia, Pa.

Application January 17, 1935, Serial No. 54,896

Term of patent 14 years

To all whom it may concern:

Be it known that I, Alexander E. Voigt, a citizen of the United States, residing at Philadelphia, in the county of Philadelphia and State of Pennsylvania, have invented a new, original, and ornamental Design for an Automobile Body, of which the following is a specification, reference being had to the accompanying drawing, forming part thereof.

Figure 1 is a side elevation of an automobile body embodying my design.

Figure 2 is a top plan view.

Figure 3 is a front end elevation and

Figure 4 is a rear end elevation of the automobile body.

I claim:

The ornamental design for an automobile body as shown.

ALEXANDER E. VOIGT.
